UNITED STATES PATENT OFFICE.

WILLIAM N. GOLDHAMER, OF ST. LOUIS, MISSOURI.

COOKING STOVE AND RANGE.

Specification of Letters Patent. Patented July 14, 1914.

1,103,140.

Original application filed August 5, 1912, Serial No. 713,351. Divided and this application filed January 13, 1913. Serial No. 741,842.

To all whom it may concern:

Be it known that I, WILLIAM N. GOLDHAMER, a citizen of the United States, residing at the city of St. Louis, State of Missouri, have invented certain new and useful Improvements in Cooking Stoves and Ranges, (being a division from my application for Letters Patent for stoves and ranges, filed August 5, 1912, Serial No. 713,351,) of which the following is a specification, reference being had to the accompanying drawings, forming a part hereof.

My invention relates generally to certain new and useful improvements in stoves and ranges used for cooking purposes and more especially in the structure or formation and mounting of the ovens thereof, the objects of my present invention being to construct and provide a cooking stove or range in which the oven is firmly supported directly by the front and rear walls of the stove or range; to provide a cooking stove or range with what might be called a built-up oven of substantial, simple, and durable construction; to provide a cooking stove or range in which the rear wall of the stove or range forms the rear wall of the oven, the amount of material in, and cost of production or manufacture of, the finished stove or range being correspondingly reduced and lessened; and to simplify the construction of, and improve generally upon, stoves and ranges of the kind stated.

To the above ends and with the above and other objects in view, my invention resides in certain novel features of construction, arrangement, and combination of parts, all as hereinafter more fully described and afterward pointed out in the claim.

In the accompanying drawings—Figure 1 is a front elevational view of a cooking stove or range embodying my present invention; Fig. 2 is a horizontal sectional view thereof taken on the line 2—2, Fig. 1; Fig. 3 is an elevational view looking against the inside of the plate or member forming the front wall of my improved stove, the same being broken away; Fig. 4 is an enlarged detail sectional view taken on the line 4—4, Fig. 1; and Fig. 5 is a perspective view of my new oven, which, in the finished stove or range, has its forward end attached directly to, and supported by, the front wall and its rearward end attached directly to, and supported by, the rear wall

of the stove or range, the rear wall of the stove or range also forming the rear wall of the oven.

Referring by numerals to said drawings, which illustrate my invention in connection with a stove or range which is otherwise of ordinary construction, 1 indicates the stove base, 2 the supporting legs for base 1, 3 the rear wall, 4—4 the side or end walls, and 5 the stove top, all of which parts are preferably of ordinary, well-known construction.

A indicates the front wall of the stove or range. This front wall A, as contemplated by my invention, is preferably formed in a single piece preferably by casting and integrally comprises a bottom horizontally-disposed piece 6, vertically-disposed end-pieces 7 and 8, and a top horizontally-disposed piece 9. These pieces form substantially a rectangular frame around the oven-door opening 10, the edges of said pieces adjacent said opening being recessed, as at 11^a, so as to accommodate the hinges of an oven door (not shown).

Formed in the center of bottom-piece 6 is a horizontally-disposed preferably rectangular opening 12, normally closed by a door (not shown), permitting ready access to the space within the stove-body beneath the oven, front wall A being mounted upon base 1 and firmly and securely fixed thereto in any suitable manner, preferably by means of stove-bolts or screws 6^a passing through the lower portion of piece 6, as shown in Fig. 1.

Top piece 9 is preferably provided with a plurality of openings adapted to receive gas burners or pipes, as shown and designated at 13, and formed in piece 7, which is preferably somewhat wider than piece 8, is an opening 14 in which is arranged a suitable grate-housing (not shown) and also suitable openings 15 and 16 communicating, respectively, with the fire-box and ash-compartment of the stove or range.

Formed integrally with front wall A adjacent the outer edge of its vertically-disposed piece 8 and projecting inwardly or rearwardly therefrom is a vertically-disposed flange 17 which lies immediately inside, and to which is suitably firmly fixed, the front edge of the corresponding end or side wall 4, vertically-disposed piece 7 of front wall A being correspondingly provided with a similar flange 17^a for the at-

tachment to front wall A of the opposite end or side wall 4, as shown particularly in Figs. 2 and 3. Likewise formed integrally with front wall A adjacent the upper edge of piece 9 is an inwardly presented horizontally-disposed flange 18 to which is suitably firmly attached and fixed the front portion of stove-top 5.

Formed integrally with pieces 6, 7, 8, and 9 of front wall A at the edges of, and extending continuously around oven-door opening 10, is an inwardly or rearwardly projecting rectangular flange; and projecting from the upper or outer face of flange 19 and lying with its outer and inner faces to the rear of the plane of the outer face of wall or plate A and forwardly of the rear edge of flange 19, and also extending continuously around oven-door opening 10, is a second or oven-abutting integral rectangular flange 11, this flange 11 with the portion of flange 19 to the rear thereof providing a right-angular seat, and serving as points of direct attachment and support, for the front edges of an oven B, as shown particularly in Figs. 2 and 4. This oven B, shown particularly in Fig. 5, is substantially a rectangular open-ended shell and comprises preferably a top wall 20, a bottom wall 21, and side walls 22-22, the said walls being bent outwardly at their rear edges to provide flanges 20^a adapted to abut flatwise against and be readily riveted or otherwise suitably attached and fixed to the rear wall 3 of the stove-body. The edges of top-wall 20 of oven B are flanged or bent downwardly and overlap, and are adapted to be fastened to, the upper edges of the side walls 22-22, and likewise the lower edges of the side walls 22-22 are flanged or bent inwardly and overlap, and are adapted to be riveted or otherwise fastened to, the side edges of bottom wall 21. To accommodate these overlapped or thickened edges of the walls of oven B, the corners of the frame formed by the flanges 19 are recessed, as at 19^a, the said oven B being adapted to neatly seat and be firmly supported at its forward end in and by, and preferably fastened, as by means of rivets, stove-bolts, or the like, or otherwise suitably fixed to, the frame formed by said flanges 19.

By my invention, the construction of cooking stoves and ranges is, as will be seen, considerably simplified and, at the same

time, the cost of production or manufacture thereof is lessened. As shown particularly in Fig. 2, oven B may be easily arranged within the stove or range body and, being fixed to, and supported at its ends directly by, walls A and 3, is firmly and rigidly held in proper position, its front open end communicating directly with oven-door opening 10; and, wall 3 forming, as will be noted, not only the rear wall of the stove or range proper, but also the rear wall of oven B, a saving of material is effected without reducing the efficiency of the stove or range for cooking purposes. Furthermore, oven B, having a riveted, built-up body, is substantial and capable of long-continued use without repairs.

I am aware that minor changes in the arrangement, construction, and combination of the several parts of my new stove or range may be made and substituted for those herein shown and described without departing from the nature and spirit of my invention.

Having thus described my invention, what I claim and desire to secure by Letters Patent is:

In a stove or range, the combination with a front wall comprising a flat plate provided within its area with a transverse oven-door opening and having an integral relatively broad rectangular flange projecting rearwardly at and around the edges of said opening and a second rectangular or oven-abutting integral flange projecting from the face of said first flange and lying with its outer and inner faces to the rear of the plane of the outer face of said plate and forwardly of the rear edge of said first flange, said second flange with the portion of said first flange to the rear thereof forming a right-angular oven-seat, of a substantially rectangular oven-shell having its front end seated in and supported by said seat, and fastening devices engaging said oven-shell and said first flange for permanently fastening said oven-shell at its front end to said plate; substantially as described.

In testimony whereof, I have signed my name to this specification, in the presence of two subscribing witnesses.

WILLIAM N. GOLDHAMER.
